(57) **CLAIM**

I claim the ornamental design for an electronic cigarette vaporizer housing plate, as shown and described.

DESCRIPTION

FIG. 1 is a top front perspective view of an electronic cigarette vaporizer housing plate.

FIG. 2 is a front elevational view of the electronic cigarette vaporizer housing plate depicted in FIG. 1.

FIG. 3 is a rear elevational view of the electronic cigarette vaporizer housing plate depicted in FIG. 1.

FIG. 4 is a left side elevational view of the electronic cigarette vaporizer housing plate depicted in FIG. 1.

FIG. 5 is a right side elevational view of the electronic cigarette vaporizer housing plate depicted in FIG. 1.

FIG. 6 is a top plan view of the electronic cigarette vaporizer housing plate depicted in FIG. 1; and,

FIG. 7 is a bottom plan view of the electronic cigarette vaporizer housing plate depicted in FIG. 1.

The broken lines in the drawings illustrate portions of the electronic cigarette vaporizer housing plate that form no part of the claimed design.

The dotted and dashed line in the drawings show a boundary of the claimed design. The claimed subject matter extends to the boundary but does not include the boundary.
